[57] CLAIM

The ornamental design for a backpack, as shown and described.

DESCRIPTION

FIG. 1 is a top, left side, perspective view of a backpack showing our new design, the fragmentary broken line showing the straps and slide fastener pull being for illustrative purposes only and forming no part of the claimed design; FIG. 2 is a front elevational view thereof; FIG. 3 is a right side elevational view thereof, the left side elevational view being a mirror image thereof; FIG. 4 is a rear elevational view thereof; and, FIG. 5 is a top plan view thereof; and, FIG. 6 is a bottom plan view thereof.
